UNITED STATES PATENT OFFICE.

EARL UNDERWOOD, OF NEW YORK, N. Y., ASSIGNOR TO KREMENTZ & COMPANY, OF NEW YORK, N. Y., A CORPORATION OF NEW JERSEY.

COLLAR-BUTTON-DISPLAY TRAY.

Application filed June 21, 1922. Serial No. 569,991.

To all whom it may concern:

Be it known that I, EARL UNDERWOOD, a citizen of the United States, residing at 644 Riverside Drive, borough of Manhattan, 5 city and State of New York, have invented a certain new and useful Improvement in Collar-Button-Display Trays; and I hereby declare the following to be a specification thereof.

10 The object of my invention is to provide a tray for displaying collar buttons that is more efficient than the conventional display tray and at the same time more decorative.

To accomplish this object I provide a 15 preferably square shape tray provided with a series of alternate parallel grooves and parallel projections, in which the collar buttons are inserted as described herein.

Fig. 1 in the accompanying drawings is a 20 plan view of the display tray showing the arrangement of the grooves, *a*, and the slightly overlapping alternate projected portions, *b*, and the inclined portion, *c*, at the top of the tray by means of which the 25 collar buttons are slid into the grooves, *a*.

In Fig. 2 we have a cross sectional view of the tray showing the grooves, *a*, and the projected portions, *b*, the rim, *d*, the bottom of the tray, *e*, and a felt pad or cushion, *f*, 30 on the bottom of the tray, also the lining, *g*.

Fig. 3 is a longitudinal sectional view of the tray showing the inclined portion, *c*, at one end and the groove in which the collar button slides.

35 The position of the collar button in the groove is shown in Fig. 4 which is an enlarged sectional detailed view of a groove.

Referring more particularly to the drawings above mentioned, the tray consists of a 40 quadrilateral wooden base with a wall or rim, *d*, preferably about an inch in height. The interior of the tray contains an added member, *h*, super-imposed upon the floor with alternate parallel grooves, *a*, and projections, *b*. The top, *h*, of the projections is 45 extended laterally slightly overlapping the

groove to secure the button in the groove and also to provide a cushion spring for the button, as will more fully appear. The interior of the tray is covered with velvet or a similar substance, *g*, which is glued in place, except at the recesses, *i*, extending under the edges, *h*, of the projections, *b*, thus permitting the material to act as a lateral spring in the recesses, *i*, or the sides of the groove. 50 This gives the desired lateral pressure against the button when it is inserted in the groove, as illustrated in Fig. 4. The collar button is thus held securely in position in the groove, and prevents one collar button 55 from rubbing against another, thus preventing the marring of the goods and the spoiling of the display.

It may thus be seen that when the collar buttons are inserted in the grooves, at the 60 inclined part of the tray, *c*, they may be slid along same until the tray is filled. The collar buttons will retain their positions in the grooves, *a*, due to the projections *b*, and the lateral pressure of the velvet in the recesses, *i*, and the tray may be exhibited flat 65 or at any desired angle to the eye. The inclined part of the tray, *c*, also permits of the removal of the collar buttons from the 70 grooves with increased facility.

Having thus described my invention, what 75 I now claim and desire to protect by Letters Patent is as follows:

A collar button display tray consisting of a base and rim, and provided with alternate 80 parallel grooves and projections, the tops of which projections, extend laterally, a lining of suitable material, glued to the interior of the tray, excepting at the recesses that extend under the edges of the projecting portions, to provide a cushion spring for the collar buttons when they are inserted in the grooves, an inclined portion at the top of the tray to permit the insertion of the collar buttons in the grooves and their removal from same with facility. 85 90

EARL UNDERWOOD.
